UNITED STATES PATENT OFFICE.

HENRY BRUNT, OF BALTIMORE, MARYLAND.

DESIGN FOR A EWER.

SPECIFICATION forming part of Design No. 22,303, dated March 21, 1893.

Application filed February 21, 1893. Serial No. 463,257. Term of patent 3½ years.

To all whom it may concern:

Be it known that I, HENRY BRUNT, a citizen of the United States, residing at Baltimore, Maryland, have invented and produced a new and original Design for a Ewer, of which the following is a specification, reference being had to the accompanying drawings, forming a part hereof.

Referring to the annexed drawings, Figure 1 is an exterior side elevation of the ewer and Fig. 2 a top view of the same.

I describe the ewer as follows: The body A at the upper end *a* is practically speroidal, and at the lower end *b* nearly cylindrical and where these two shapes come together is a hollow curve *c*. The extreme end of the portion *b* of the body is curved inward and decorated with a band *B*, the leading feature of which is a series of points extending upward. Below this band is a thin beaded circular base *d*.

C is the neck, circular in cross section, and flared slightly outward. At one side the flare is considerably extended, to form a lip *D* and on each side of the ewer the edge of this lip 5 and the neck in the rear of it is decorated with

a figure in relief resembling a cornucopia the point of which leads nearly to the base of the neck and below the lip *D*. The extreme edge of the lip and neck is indented and beaded, and where the configuration crosses the center line of the cornucopia is a deeper and nearly circular depression *e*.

Beginning at the junction of the body *A* and the neck *C*, and falling over the former, is a decorated collar *E* the lower edge of which corresponds in configuration with the band *B*, but reversed in position as regards the points.

F is the handle which rises from the body *A* and after flaring slightly outward falls in and is connected by a branched end *f* to the rear side of the neck which is provided with a scroll. This scroll is apparently grasped by the handle.

I claim as my invention—

The design for a ewer as herein shown and described.

HENRY BRUNT.
